(57) **CLAIM**

The ornamental design for an electronic article surveillance apparatus with attachment, as shown and described.

DESCRIPTION

FIG. 1 is a left handed top perspective view of an electronic article surveillance apparatus with attachment in an unengaged state having an identical right hand view;

FIG. 2 is a left handed side elevational view of the apparatus in an unengaged state;

FIG. 3 is a right handed side elevational view of the apparatus in an unengaged state;

FIG. 4 is a top plan view of the apparatus in an unengaged state;

FIG. 5 is a bottom plan view of the apparatus in an unengaged state;

FIG. 6 is a front end perspective view of the apparatus in an unengaged state; and,

FIG. 7 is a back end perspective view of the apparatus in an unengaged state.
